UNITED STATES PATENT OFFICE

93,697

DESIGN FOR A SERVICE STATION BUILDING OR THE LIKE

Charles A. Urbanek, Chicago, Ill., assignor to
Standard Oil Company, Chicago, Ill., a corpora-
tion of Indiana

Application May 14, 1934, Serial No. 51,781

Term of patent 7 years

To all whom it may concern:

Be it known that I, CHARLES A. URBANEK, a citizen of the United States, residing at Chicago, in the county of Cook and State of Illinois, have invented a new, original, and ornamental Design for a Service Station Building or the like, of which the following is a specification, reference being had to the accompanying drawings, forming part thereof, in which:

Figure 1 is a front elevation of a service station building according to my new design;

Figure 2 is a horizontal section, taken at window level, and showing the outline of the exterior

walls of the service station building of Figure 1 shown to a somewhat reduced scale; and

Figure 3 is a front view of the tower portion of the service station building of Figure 1 shown to a somewhat enlarged scale. Said tower portion constitutes the dominant feature of my new design.

I claim:

The ornamental design for a service station building or the like, substantially as shown and described.

In witness whereof, I have affixed my signature.

CHARLES A. URBANEK.
